MULTIPLE SPRAY GUN

Harold L. Striegel, Eric Gustafsson, and John W. Baur, Chicago, Ill., assignors to Binks Manufacturing Company, Chicago, Ill., a corporation of Delaware

Application May 7, 1945, Serial No. 592,450

4 Claims. (Cl. 91—45)

1

The present invention relates to spray guns and more particularly to a multiple type of spray gun.

Among the objects of the invention is to provide a novel spray gun structure for simultaneously spraying different character coating material in given relation, and which has a plurality of spray gun components or units which are relatively adjustable, as angularly, and each of which units sprays a different kind or character of material, so that the combined or aggregate sprays will produce a given coating effect or design. The spray gun units may be carried by a common body to which the air for effecting the spraying of the material in the individual units may be supplied and controlled, and may be adjustably connected to said body to obtain the desired relative adjustment of the units and the sprays therefrom, whereby the sprays from the individual units may be varied toward or from each other as desired to effect the desired coating character or design on the target or surface being coated. The individual air supplies to the gun units may be individually varied, as by valves carried by the body of the device.

There are certain coating materials which are miscible and cannot be initially mixed. Therefore, by the present invention they are separately sprayed and permitted to mix only at the target surface.

There are other coating materials which will react with each other chemically and also in that case it is desirable that they be separately sprayed and not permitted to mix until they hit the target.

In some cases, the different coating materials will coalesce if mixed, as would be the case of a coating material containing a latex and another containing a latex coagulant, and therefore the present invention comprehends the spraying of the materials separately and to prevent the coalescence until they hit the target.

Another object of the invention is to provide a common means, such as a manually operable trigger, carried by the body and having a member connected to the means, such as needle valves, for controlling the supply of the material to and through each spraying unit, with means for adjusting the timing or relation of operation of the material-control valves.

Other objects, advantages, capabilities, features and the like are comprehended by the invention as will later appear and as are inherently possessed by the invention.

Referring briefly to the drawings:

2

Fig. 1 is a view in side elevation of a multiple spray gun constructed in accordance with the invention;

Fig. 2 is a top plan view thereof;

Fig. 3 is a sectional view taken in a plane represented by line 3—3 in Fig. 1 of the drawings;

Fig. 4 is a sectional view taken in planes represented by line 4—4 in Fig. 2 of the drawings;

Fig. 5 is a transverse sectional view taken in planes represented by line 5—5 in Fig. 1 of the drawings;

Fig. 6 is a sectional view taken in a plane represented by line 6—6 in Figs. 1 and 4 of the drawings;

Fig. 7 is a fragmentary sectional view taken in a plane represented by line 7—7 in Fig. 1 of the drawings;

Fig. 8 is a fragmentary sectional view taken in a plane represented by line 8—8 in Fig. 7 of the drawings;

Fig. 9 is a fragmentary sectional view, on an enlarged scale, taken in a plane represented by line 9—9 in Fig. 2 of the drawings;

Fig. 10 is a side view of the nozzle part shown in Fig. 9;

Fig. 11 is a front end view of the nozzle part shown in Fig. 10;

Fig. 12 is a rear end view of the nozzle part shown in Fig. 10;

Fig. 13 is a fragmentary sectional view taken in planes represented by lines 13—13 in Fig. 9 of the drawings; and

Figs. 14, 15, and 16 are views by way of illustration of different types of designs effected by spraying with the invention.

Referring more in detail to the drawings, an illustrative embodiment of the invention is shown as comprising a body 1 having a rearward part 2 from which depends a handle or hand grip 3 and also having at the top a hook 4 by which the gun may be hung from any suitable means.

In the handle are provided bores or passages 5 and 6 (see Fig. 4), valve chambers 7 and 8 and an air passage 9 extending from the chamber 7 to an air passage 10 provided in the body 1 and the extension 2 (see Fig. 4). At the lower end of the passage or bore 5 is a plug 11, and at the lower end of the passage 6 is provided a coupling or union 12 having means, as a threaded portion 13, for the suitable connection of a compressed air duct, such as a hose or the like (not shown). The bore or passage 10 extends forward in the body 1 to a cross bore 14 (see Fig. 3) provided in the body 1. Said cross bore is closed 55 at an end thereof by a suitable plug 15 (see Fig.

3). From the cross passage 14 extend air passages 16 (see Figs. 3 and 9) and 17 and 18 (see Fig. 3), respectively leading to valve chambers 19 (see Figs. 3 and 9) and 20 and 21 (see Fig. 3), and respectively having valve seats 22, 23 and 24 (see Fig. 3). In the passage 10 extends an elongated valve body 25 (see Figs. 3, 4, 5 and 9), the forward end of which has a valve seating part 26 for seating on the seat 22, and the rear end of which has a threaded portion 27 adjustable thereby in a bushing-nut 28 threaded into the rear end of the bore or passage 10 (see Figs. 3 and 4) and having also a finger piece or knob 29. On the stem 25 within the bore 10 is a washer 30 which abuts against a cross pin 30a extending through the stem 25, and in the nut 28 is provided suitable packing 30d against which is pressed a washer 30c by a spring 30b interposed between the washers 30 and 30c.

Referring to the handle 3, in the chamber 7 is located a valve cage or shell 31 (see Fig. 4) having a seat 32 fitted with a sealing engagement between the chambers 7 and 8, shell 31 having openings 33 for affording communication between a chamber 34 within the shell 31 and the chamber 7 surrounding said shell 31. The forward end of the shell 31 has a screw plug 35 threaded in a forward portion of the handle 3, as shown in Fig. 4, and said plug 35 has a forward packing gland 36 to which is threaded a cap 37 (see Figs. 1 and 4). Slidable in the plug 35, gland 36 and cap 37, and extending through said chamber 34 is a valve stem 38, the forward end part 39 of which is located at the rear of the trigger 40 which engages the stem 38-39 when the trigger 40 is pressed back by the user of the gun, and at the rear end portion of the stem 38 is carried a valve part 41 adapted to seat on the valve seat 32 by the force of a spring 42 pressing at its forward end against the valve 41 and at its rear end against the rear extended end portion 43 of the chamber 8. The valve 41 may have a stub 44 for extending into the forward end of the spring 42 to maintain it in alignment. The trigger 40 is pivotally connected by way of pivot pins 45 carried by a lower part 46 of the body 1 (see Figs. 1 and 4).

At the forward part of the body 1 are provided adjustable valves 47 and 48 (see Fig. 3) adapted to seat on the valve seats 23 and 24, which valves have stems 49 and 50 extending through the chambers 20 and 21 and through nut-bushings 51 and 52 threaded at the forward end of the body 1 and threaded to adjustably receive the threaded parts 53 and 54 of the stems 49 and 50 for adjustment therein, the outer ends of the stems 49 and 50 having finger knobs or heads 55 and 56. Each member 51 and 52 has a socket in which is a spring 57 (see Fig. 3) normally pressing at one end against a washer 58 abutting a cross pin 59 carried by the stems 49 and 50, and at the other end pressing against a packing 57a in the head 51, the spring 57 acting to normally urge the valves 47-48 toward closing position when the knob 55, 56 is operated to adjust the stem 49, 50.

In the forward part of the body 1 are provided a plurality of vertical bores 60, 61 and 62 in each of which is a pivot plug 63 (see for example Fig. 9) having a head 64, seated and sealed on the top of the body 1, a shank or body 65 having an annular channel 66, a cross passage 67, and an axial passage 68 communicating with the cross passage 67 and leading to the lower end of the plug 63, this lower end of the plug having a

threaded portion 69. In the lower or underside of the body 1 are provided sockets 70 around the threaded part 69 and in each of these sockets is a gasket 71 or the like. The annular channels 66 are, respectively, in communication with the valve chamber 19, or valve chamber 20, or valve chamber 21, as the case may be, depending upon which channel is referred to.

To each threaded portion 69 of the pivot plug 63 is threaded a spray gun unit 72, or 73, or 74, as the case may be, all spray gun units being alike. Each spray gun unit has an upper hub 75 screwed to the threaded lower end portion 66 of the pivot plug 63. In this way each gun is angularly adjustable about the axis of the pivot plug 63. Normally, the position of the middle gun 72 need not be adjusted, but the side guns 73 and 74 are adjusted relative to the middle gun 72. However, the middle gun may also be adjusted in certain cases when it is desired to do so.

Each gun unit has a gun body 76 having a forwardly extending hub 77, a rearwardly extending hub 78 and a downwardly extending hub 79 (see for example Fig. 9). To the hub 77 is threaded a material and air nozzle unit 80 on the forward end of which is seated an air nozzle cap 81 held in place by a coupling ring 82, the cap 81 also having horns 83 for projecting side air jets for effecting flat spraying. This construction is shown in the McMartin Patent No. 2,249,771, granted July 22, 1941, and more specific description thereof is herein deemed unnecessary. The material to be sprayed in and by each gun component 72, or 73, or 74 passes by way of the passage 84 (see Fig. 9); passage 85, nozzle tip 86, and orifice 87; and the air passes by way of passages 88, 89, 90 and 91 to the orifice 87, and also by way of passages 92, 93, 94, 95 and 96 to the side jet orifices 97 in the horns 83. The flow of air is controlled and regulated by adjusting the air valves 25-26, 41-49, and 48-50.

The flow of the coating material is controlled by a needle valve 98 having a tip 99, and having its rear end extending into the hub 78 at the rear portion of the gun unit (see Fig. 9), such rear end portion passing through suitable packing 100 and having threaded connection with the forward end portion 101 of a stem 102. To the rear end of the hub 78 is threaded a cap 103 which has a flanged part 104 provided with a hole for the passage of the stem 102, and between this flange 104 and a similar flange 105 at the forward end of the stem 102 is located a spring 106 which normally urges the needle valve 98-99 to closed position, and which yields to permit the opening of the needle valve 98-99 when the trigger is pressed by the user of the device. Between the packing 100 and the inner end of the cap 103 is interposed a spring 100a.

The rear end portion of the stem 102 is threaded and on this is threaded an adjustable thimble or collar 107 (Figs. 4, 6 and 8) having at its ends heads or flanges 108 and 109 which may be nut shaped, or otherwise for turning the thimble or collar on the stem 102 and adjusting it therewith to regulate the timing of the opening of the needle valves 98-99. A lock nut 110 is provided on the free end of the stem 102 to hold the collar or thimble 107 locked in adjusted relation.

The upper part of the trigger 40 has spaced walls 111 to which are fixed side arms 112, and in these side arms 112 are carried the shanks 113 (see Figs. 6 and 7) of forks 114 having spaced

fingers 115 which straddle the bodies of the thimbles 107 on the stems or shanks 102. The rear edge portions of the fingers 115 have tapered or curved parts 116 to substantially abut squarely with the heads 108 of the thimbles 107 when the trigger is pulled back to operate the needle valves.

The inner ends of the stems 113 have threaded parts 117 (see Fig. 7) which are secured to the sides of a fork piece having fingers 118 for spanning the body of the thimble 107 of the middle gun unit. A suitable washer 119 may be placed between each finger 118 and the side wall 111 of the trigger, as shown in Fig. 7. It will be seen that the forks 114 and the fork 118 are pivotally supported by the trigger 40 so that when the trigger is pulled back the forks 114 and 118 may have an angular play for the fingers 115 to suitably squarely abut the rear flange 108 of the thimble 107.

Normally, the spring 106 in each gun unit holds the needle valve 98-99 closed. The thimbles are so adjusted on the stems 102 that there is a clearance between the rear collar 108 and the fingers 118 and 115 of the forks. See Fig. 6 by way of illustration. When the trigger is pulled back it will first engage the air valve stem 39 to admit air to the air passage 10 and thence to the valves 22-26, 23-47, and 24-48 for the air to be first projected through the air nozzles 81 and side jet nozzles 91. Further movement of the trigger 40 will bring the fingers 118 (see Figs. 4 and 6) into engagement with the collar 108 of the thimble 107 of the middle gun, and then the fingers 115 into engagement with the collars 108 of the thimbles 107 of the side guns. The latter engagements may be successive or simultaneous, or all may be simultaneous, as desired. The effect in each and all such cases is to open the needle valves in sequence or simultaneously as may be desired. Varying the position of the thimbles 107 on their respective stems 102 will vary the relative timing of the opening of the needle valves to obtain different effects of spraying.

One of the objects of the device is to adjust the relation of the gun units, which is done angularly about the axis of the pivot plug 63 so that the coating material may be sprayed from the gun units on the target more or less proximate, depending upon the resultant effect to be produced. This adjustment is had by loosening the threaded connection between the gun unit and the plug 63 and turning the gun unit to the desired angular relation and then tightening said connection. By adjusting the air control valves 22-26, 23-47, and 24-48 the resultant effect may also be varied as desired.

An object of the device is to use different kinds of coating material in the respective gun units, such as different colored material. To illustrate, reference may be made to Figs. 14, 15 and 16 showing a few examples of any number of different patterns that may be effected. In Fig. 14 is shown a pattern in which the background 120 is of a predominant color, such as a light color, which may be sprayed by the middle gun unit, and the parts 121 may be sprayed from one of the side gun units of another color, such as red, brown or yellow, etc., and the parts 122 may be sprayed from another of the side gun units of still another color, such as blue, green or the like.

In Fig. 15, the background color 123 may not be so prominent, and the interspersed other color areas 124 and 125 may be more prominent.

In Fig. 16 the background color 126 is of minor

value, while the other colors 127 and 128 are interspersed in major proportions.

All of these effects are obtained in one spraying operation, that is, at the same time or simultaneously, and does not require the application of each color separately and at different times, whereby one must be allowed, as heretofore, to sufficiently dry or set before the other was applied, and wherein one color had to be superimposed upon another. The spray gun of the present invention applies all the colors, or different kinds of material, at once and there is no superimposing of one color or kind on another, hence, considerable time and material are saved.

15 While we have herein described and upon the drawings shown an illustrative embodiment of the invention, it is to be understood that the invention is not limited thereto but comprehends other constructions, arrangements of parts, details, features and the like without departing from the spirit of the invention.

Having thus disclosed the invention, we claim:

1. A multiple spray gun of the character disclosed, comprising, in combination, a body having a hand grip, a trigger movably supported on the body adjacent the hand grip, air passages in the body extending to the forward end thereof, an air valve within the body for controlling the entire flow of air through said air passages, a plurality of spray gun units supported pendently from the forward end of the body, each spray gun unit including a nozzle and having a continuous air flow connection with the air passages in the body, means to conduct material to each spray gun unit, a normally closed needle valve for controlling flow of material from each unit, each unit being movable freely by hand about an axis which is substantially vertical when the spray gun is held in normal horizontal position, and means adjustably coupling the trigger to the needle valves so that the trigger when moved may cause flow of material from the nozzles after flow of air is started and may initiate flow from any one of the nozzles before or after or simultaneously with flow from any other nozzle and irrespective of the positions of the units.

2. A multiple spray gun of the character disclosed comprising, in combination a body having air passages extending to the forward part of the body, an air valve in the body for controlling flow of air through the body, a trigger pivoted on the body and adapted to operate said air valve, a plurality of spray gun units depending from the forward part of the body, a plurality of hollow members swiveled on the body and communicating with the air passages, each spray gun unit being secured to a hollow member so as to turn therewith relative to the body and so as to receive air therefrom in all positions into which it may turn, means to feed material to each spray gun unit, needle valve means in each unit to control flow of material from the unit, and means adjustably coupling the trigger to the needle valve means so that the trigger may control flow of air and material in the manner desired.

3. A multiple spray gun of the character disclosed, comprising, in combination, a body having air passages extending therethrough, a plurality of spray gun units independently and movably supported upon the body so that the angles of the sprays may be varied, each unit including a nozzle and having air and material passages 70 terminating in the nozzle, means for delivering

material to each unit through its material passages, a needle valve in each unit for controlling the flow of material out of the nozzle, a spring normally closing each needle valve, each unit supporting means consisting of a hollow member secured to the body and having communication with the air passages in the body and delivering air to the unit, the unit turning about the axis of the hollow member when its angularity is to be varied, a trigger pivoted on the body, an air valve in the body controlled by the trigger to admit compressed air to said air passages and hence to said nozzles, and means connecting the trigger with the needle valves to permit opening of the needle valves irrespective of the angular positions of said units.

4. A multiple spray gun of the character disclosed, comprising, in combination, a body having air passages extending therethrough, a plurality of spray gun units, means independently and ppendently supporting the units upon the body so that the angles of the sprays may be manually varied, each unit including a nozzle and having air and material passages terminating in the nozzle, means for delivering material to each unit through its material passages, a needle valve in each unit for controlling the flow of material out of the nozzle, a spring normally closing each needle valve, a trigger pivoted on

the body, an air valve in the body controlled by said trigger to admit compressed air to said air passages and hence to said nozzles, each needle valve having a valve stem extending outside of the unit and having screw threads thereon, an adjustable thimble having a head and engaged with the screw threads on each valve stem, means to hold the adjustable thimble in adjusted positions, means fixed to the trigger and straddling the thimbles and adapted to abut the heads thereof, the thimble being of sufficient length to permit said trigger-affixed means to move a certain distance before the heads are abutted, the trigger operating to lift the corresponding needle valve off its seat whenever the thimble head is engaged by said trigger-affixed means.
